United States Patent Office

Des. 185,295
Patented May 26, 1959

185,295

SUPPORT BASE FOR DESK MEMORANDUM PAD, OR SIMILAR ARTICLE

Herbert W. Marano, Summit, N.J., assignor to Wilson
Jones Company, Elizabeth, N.J., a corporation of Massachusetts

Application September 30, 1958, Serial No. 52,816

Term of patent 14 years

(Cl. D74—1)

I claim:

The ornamental design for a support base for desk memorandum pad, or similar article, as shown.
